Des. 204,741

Patented May 17, 1966

204,741

PULL FOR DRAWERS, DOORS AND THE LIKE

Matthew M. Adams, 602 Fairview Ave., Arcadia, Calif.

Filed May 17, 1965, Ser. No. 85,315

Term of patent 3½ years

(Cl. D10—8)

FIGURE 1 is a side elevational view of a pull for drawers, doors and the like, showing my new design;

FIGURE 2 is a frontal view thereof; and

FIGURE 3 is a rear view thereof.

I claim:

The ornamental design for a pull for drawers, doors and the like, as shown.
